UNITED STATES PATENT OFFICE.

WALTER J. RICHARDS, OF NORWOOD, OHIO, ASSIGNOR TO ALLIS-CHALMERS COMPANY, A
CORPORATION OF NEW JERSEY.

MOTOR-CONTROL SYSTEM.

No. 872,684.

Specification of Letters Patent.

Patented Dec. 3, 1907.

Application filed April 29, 1907. Serial No. 370,980.

To all whom it may concern:

Be it known that I, **WALTER J. RICHARDS**,
citizen of the United States, residing at Nor-
wood, in the county of Hamilton and State
of Ohio, have invented certain new and use-
ful Improvements in Motor-Control Systems,
of which the following is a full, clear, and ex-
act specification.

My invention relates to motor control systems and particularly to the automatic control of motors for operating the lifting tables of rolling mills.

15 In the operation of three-high rolling mills it is necessary to raise and lower the tables which receive and support the material to be rolled on either side of the rolls themselves. Generally heretofore this movement of the lifting tables has been obtained by means of steam engines or other fluid operated mechanism. But in many modern rolling mills now being installed it is being found desirable to substitute electricity for steam as a motive power. So far as I am aware, however, no scheme has yet been devised for obtaining the proper movement of the lifting tables of three-high rolling mills by electric motors, for these tables not only require a reciprocating movement but must be stopped very accurately in order to allow the ingot to be caught by the rolls.

20

25

30

It is the object of my invention to provide a system of electrical drive for these tables whereby their proper operation is insured and to a great extent rendered automatic.

My invention broadly comprises the combination of an electric motor, and a controller therefor arranged to make automatically a complete cycle while the motor makes a pre-determined number of rotations.

Somewhat more specifically my invention comprises the combination of a motor, a rotatable member driven thereby, a reciprocal controller for the motor arranged to be moved by said rotatable member, and connections whereby the movement of said controller in one direction controls the electro-motive force impressed on the armature of the motor, and the movement in the other direction controls the amount of resistance in a local circuit supplied by the motor operating as a braking dynamo.

55 Other features of my invention will appear

from the description and drawings and will be particularly pointed out in the claims.

Figure 1 shows diagrammatically one embodiment of my invention; and Fig. 2 shows a cross section of the magnetic brake.

The three rolls 10, 11 and 12 of a three-high rolling mill may be driven in any desired manner. Lifting tables 12 and 13 are arranged in the usual manner on each side of these rolls to receive and support the ingot, bloom or billet 14 to be rolled, and may be raised and lowered to bring the ingot 14 between the rolls 10 and 11 or between the rolls 11 and 12. This is accomplished through bell-crank levers 15 connected to the supports of said tables and joined to a gear wheel 16 by means of a connecting rod 16^a. One half rotation of the gear wheel 16 raises the tables 12 and 13 and the next half rotation lowers said tables. Another gear wheel 17 is arranged to move at twice the angular speed of the gear wheel 16, both of these gear wheels being driven by a motor 18 through any suitable train of gearing 19. For the sake of simplicity this train of gearing is here represented by a single gear wheel. A magnetic brake 20 coöperates with the gear 19 or with some other of the parts driven by the motor 18 and when energized tends to stop said motor and all of the parts driven thereby.

The effect of the magnetic brake may be regulated by a rheostat 21. The field 22 of the motor 18 may be reversed by the reversing switch 23. The motor is controlled by means of the controller 24, the reciprocable arm 25 of which is arranged to be driven from the gear 17 through suitable connecting mechanism 26, the arm 25 making a complete reciprocation for each rotation of the gear 17. Preferably the connecting mechanism 26 is so arranged that it may be disconnected from the gear 17. 90 95

The current for the various electrically operated devices may be obtained from any desired source, as through the switch 27. 100 When this switch is closed and the arm 25 is in its lowest position the motor may be started by depressing the button 28, thus moving the switch 29 to its upper position to complete the circuit through the solenoids 30 105 and 31. The former when energized raises or holds raised the switch 29, while the solenoid 31 raises the switch 32. Unless the arm 25 is in off position the sector 33 which is attached to said arm keeps the button 28 from 110

being depressed, while movement of the arm 25 and sector 33 from off position raises the button 28 if it has been kept depressed.

- The switch 32 in its upper position completes the circuit of the armature 18 through the bar 34, arm 25 and resistance 35. The field circuit of the motor is always complete when the switches 27 and 23 are closed, but movement of the arm 25 cuts the resistance 36 into and out of said field circuit. As soon as the armature circuit of the motor is completed said motor begins to drive the gear wheels 19, 17, and 16, moving the tables 12 and 13 either up or down as the case may be and the arm 25 first up and then down. As the arm 25 moves upward it gradually cuts the resistance 35 out of the armature circuit to cause said motor to speed up. It also cuts the resistance 36 into the motor field circuit to help in this speeding up while giving the motor a strong field for its starting. The last section 37 of the resistance 35 is adjustable to regulate the acceleration, both positive and negative, of the motor 18.
- When the resistance 35 has been completely cut out the resistance 36 is momentarily cut out of the field circuit to raise the counter-electromotive force of the motor. While the resistance 36 is in circuit, the arm 25 leaves the contact bar 38 to break the circuit of the solenoids 30 and 31, thus allowing the switches 29 and 32 to drop to their lower position. The dropping of the switch 29 connects in circuit the magnetic brake 20 with its rheostat 21, and of the switch 32 disconnects the motor armature from its supply circuit and connects it upon itself through the solenoid 39 and the resistance 35 so that it will act as a braking dynamo. On account of the increased electromotive force of the motor very little current is flowing at this time and consequently there is but little arcing as the switch 32 breaks the motor armature circuit. The solenoid 39 closes the switch 40 to short circuit whatever part of the resistance 35 may be above the arm 25 at any point in the descent of the latter. The arm 25 has now reached its uppermost position and has begun its descent. While it is descending the moving parts are being retarded by the action of the magnetic brake 19 and of the braking dynamo 18. The effect of the latter is maintained approximately constant because on account of the connection made by the switch 40 the descent of the arm 25 cuts the resistance 35 gradually out of the local circuit supplied by said armature. This local circuit extends from the armature 18, through the switch 32 in its lower position, the solenoid 39, that part of the resistance 35 which is below the arm 25 at any time, along the arm 25 to the contact bar 34, and through the switch 40 to the armature 18. By the time the arm 25 has returned to its lowest position and the

tables 12 and 13 have been moved to their extreme lower or upper positions as the case may be, the motor 18 and other moving parts have been brought to a stand-still. When necessary the operator can control this stopping point to some extent by the rheostat 21 but generally this rheostat and the resistance section 37 may be permanently adjusted to obtain the stopping of the motor at the desired point automatically. As soon as the motor 18 has stopped, the solenoid 39 is deenergized and the switch 40 is allowed to open. The ingot may now be sent through the rolls after which the operation above described may be repeated by depressing the push-button 28.

Should it ever be necessary or desirable to obtain less than complete movements of the movable parts this may be done by moving the switch 41 into the position shown in dotted lines to energize the solenoids 30 and 31. The movement will then continue as long as said switch remains in such position and will stop as soon after it is moved away therefrom as the various braking devices are able to obtain their effect.

The various parts of the resistance 35 may be proportioned to allow for the different rates of speed of the arm 25 in the different parts of its movement. Or if desired the connecting mechanism 26 may be arranged to cause a substantially uniform speed of said arm. By means of the switches 23 and 41 backward movement of the motor may be obtained when necessary.

Various modifications in the precise system here shown and described may be made without departing from the spirit and scope of my invention and the control system shown may be applied to other uses than for the operation of rolling mill tables. All such modifications and uses I aim to cover in the following claims.

What I claim as new is:

1. A rheostat comprising a plurality of resistance sections, means for cutting said sections into and out of circuit, and independent means of varying the resistance of one of said sections.
2. In combination, a sectional resistance, and a relatively movable arm for cutting sections of said resistance into and out of circuit, one of the resistance sections controlled by said arm being adjustable.
3. In combination, an electric motor, a sectional resistance, means for cutting the sections of said resistance into and out of the armature circuit, and means for varying the resistance of one of said sections independently of the aforesaid means.
4. In combination, an electric motor, a source of current supply, a variable resistance, a reciprocable arm for varying said resistance, and connections controlled by said arm whereby movement of the same in

One direction varies the amount of said resistance in circuit with the motor and said source of supply in series, and movement in the other direction varies the amount of said 5 resistance in circuit with the motor alone.

5. In combination, an electric motor, and a reciprocable controller therefor arranged when moved in one direction to vary the electromotive force impressed on the motor 10 armature, and when moved in the other direction over the same path to vary the resistance in a local circuit supplied by the motor armature.

6. In combination, an electric motor, a 15 rotary member driven thereby, and means for controlling the electromotive force impressed on the motor armature during one portion of a rotation of said member and for controlling the action of the motor as a braking dynamo during the remainder of said 20 rotation.

7. In combination, an electric motor, mechanism driven thereby, and a controller for the motor also driven thereby and arranged to make a complete cycle for each 25 half cycle of the driven mechanism.

8. In combination, an electric motor, mechanism driven thereby, and a controller also driven thereby and arranged to make 30 a plurality of complete cycles for each complete cycle of the driven mechanism.

9. In combination, an electric motor, and a controller therefor arranged to make automatically a complete cycle while the motor 35 makes a predetermined number of rotations in the same direction.

10. The combination of a motor, and a controller therefor arranged as it is moved in one direction to control the electromotive 40 force impressed on the motor and as it is moved over the same path in the other direction to control the action of the motor as a braking dynamo in discharging through a local circuit.

45 11. The combination of a motor, a rotatable member driven thereby, a reciprocable controller for the motor arranged to be moved by said rotatable member, and connections whereby the movement of said controller in one direction controls the electromotive force impressed upon the armature of the motor, and movement in the other direction controls the amount of resistance in a local circuit supplied by the motor armature 50 as a braking dynamo.

12. In combination, an electric motor, a magnetically operated switch in the motor armature circuit, and a reciprocable controller which as it is moved in one direction controls the resistance in the armature circuit 60 and when it reaches its limit of movement in this direction causes the opening of said switch.

13. In combination, an electric motor, a 65 magnetically operated switch in the motor

armature circuit, and a reciprocable controller which as it is moved in one direction controls the resistance in the armature circuit and when it reaches a predetermined point in its movement causes the opening of said 70 switch.

14. In combination, an electric motor, a magnetically operated switch in the motor armature circuit, and a reciprocable controller driven by the motor and arranged when 75 moved in one direction to control the resistance in the armature circuit and when it reaches a predetermined point in its movement to cause the opening of said switch.

15. In combination, an electric motor, a 80 magnetically operated switch arranged when in one position to complete the motor armature circuit and when in another position to connect the armature on itself, and a reciprocable controller driven by the motor and 85 arranged when moved in one direction to vary the electromotive force impressed on the armature and when it reaches its limit of movement in this direction to cause movement of said switch to connect the armature 90 upon itself.

16. In combination, an electric motor, a magnetically operated switch arranged when in one position to complete the motor armature circuit and when in another position to 95 connect the armature on itself, and a reciprocable controller arranged when moved in one direction to vary the electromotive force impressed on the motor armature and when it reaches its limit of movement in this direction to cause movement of said switch to 100 connect the armature upon itself.

17. In combination, an electric motor, a magnetically operated switch arranged when in one position to connect the motor to a 105 source of current supply and when in another position to connect the motor armature upon itself, and a reciprocable controller driven by the motor and arranged when moved in either direction to vary the resistance in the 110 motor armature circuit and when it reaches its limit of movement in one direction to cause movement of said switch from one position to the other.

18. In combination, an electric motor, a 115 magnetically operated switch arranged when in one position to connect the motor to a source of current supply and when in another position to connect the motor armature upon itself, and a reciprocable controller arranged 120 when moved in either direction to vary the resistance in the motor armature circuit and when it reaches its limit of movement in one direction to cause movement of said switch from one position to the other.

19. In combination, an electric motor, an electric brake therefor, a magnetically operated switch arranged when in one position to control the motor armature circuit and when in another position to control the electric 130

brake circuit, a reciprocable controller for the motor arranged when it is moved in one direction to vary the electromotive force impressed on the motor armature and when it reaches the limit of movement in said direction to cause movement of said switch to complete the brake circuit, and means for driving said controller from the motor.

20. In combination, an electric motor, an electric brake therefor, a magnetically operated switch arranged when in one position to control the motor armature circuit and when in another position to control the electric brake circuit, and a reciprocable controller for the motor arranged when it is moved in one direction to vary the electromotive force impressed on the motor armature and when it reaches the limit of movement in said direction to cause movement of said switch to complete the brake circuit.

21. In combination, an electric motor, an electric brake therefor, a magnetically operated switch arranged when in one position to control the motor armature circuit and when in another position to control the electric brake circuit, a reciprocable controller for the motor and driven thereby arranged when it is moved in one direction to vary the electromotive force impressed on the motor armature and when it reaches the limit of movement in said direction to cause movement of said switch to complete the brake circuit, and means for varying the effect of said brake.

35. 22. In combination, an electric motor, an electric brake therefor, a magnetically operated switch arranged when in one position to control the motor armature circuit and when in another position to control the electric brake circuit, a reciprocable controller for the motor arranged when it is moved in one direction to vary the electromotive force impressed on the motor armature and when it reaches the limit of movement in said direction to cause movement of said switch to complete the brake circuit, and means for regulating the effect of said brake.

23. In combination, an electric motor, a magnetically operated switch in the motor armature circuit, a reciprocable controller which as it is moved in one direction controls the resistance in the armature circuit, and when it reaches its limit of movement in this direction causes the opening of said switch, and connections whereby the controller increases the field strength of the motor while said switch is being opened.

24. In combination, an electric motor, a magnetically operated switch arranged when in one position to complete the motor armature circuit and when in another position to connect the armature on itself, a reciprocable controller arranged when moved in one direction to vary the electromotive force impressed on the motor armature circuit and

when it reaches its limit of movement in this direction to cause movement of said switch to connect the armature upon itself, and connections whereby the controller causes an increase in the counter-electromotive force of the motor while said switch is being so moved.

25. In combination, an electric motor, a magnetically operated switch arranged when in one position to connect the motor to a source of current supply and when in another position to connect the motor armature upon itself, a reciprocable controller arranged when moved in either direction to vary the resistance in the motor armature circuit and when it reaches the limit of movement in one direction to cause movement of said switch from one position to the other, and connections whereby the controller increases the field strength of the motor while said switch is being so moved.

26. In combination, an electric motor, a magnetically operated switch arranged when in one position to connect the motor to a source of current supply and when in another position to connect the motor armature upon itself, a reciprocable controller arranged when moved in either direction to vary the resistance in the motor armature circuit and when it reaches a predetermined point in its movement to cause movement of said switch from one position to the other, and connections whereby the controller increases the field strength of the motor while said switch is being so moved.

27. In combination, an electric motor, an electric brake therefor, a magnetically operated switch arranged when in one position to control the motor armature circuit and when in another position to control the electric brake circuit, a reciprocable controller for the motor arranged when it is moved in one direction to vary the electromotive force impressed on the motor armature circuit and when it reaches the limit of movement in said direction to cause movement of said switch to complete the brake circuit, and connections whereby the controller increases the field strength of the motor while said switch is being so moved.

28. The combination in a rolling mill, of a lifting table, a motor for operating said lifting table, and means for controlling said motor in response to the movement of the lifting table.

29. The combination in a rolling mill, of a lifting table, a motor for operating said table, and a controller operated by the movement of said table to stop the motor at each of its extreme positions.

30. The combination in a rolling mill, of a lifting table, electrically operated means for raising and lowering said table, and means for automatically controlling the aforesaid means.

100

105

110

115

120

125

130

31. The combination in a rolling mill, of a lifting table, electrically operated means for raising and lowering said table, and means operated by and controlling the aforesaid means.
32. The combination in a rolling mill, of a lifting table, an electric motor for operating said table, and an automatic controller for said motor arranged during part of each movement of the lifting table to control the supply of electrical energy to said motor and during the rest of the movement to control the action of said motor as a braking dynamo.
33. The combination in a rolling mill, of a lifting table, an electric motor for operating said table, and means operated by said motor and arranged as said table leaves one of its extreme positions to control the electrical energy supplied to said motor and as said table approaches the other extreme position to control the braking effect on said motor.
- In testimony whereof I affix my signature, in the presence of two witnesses.
